UNITED STATES PATENT OFFICE.

WILFRED B. GODDARD, OF SAN FRANCISCO, CALIFORNIA.

DESIGN FOR A LIGHTING FIXTURE.

Application filed December 6, 1923. Serial No. 7,966. Term of patent 3½ years.

To all whom it may concern:

Be it known that I, WILFRED B. GODDARD, a citizen of the United States, and a resident of the city and county of San Francisco, State of California, have invented a new, original, and ornamental Design for a Lighting Fixture, of which the following is a specification, reference being had to the accompanying drawing, forming part thereof.

The drawing is an elevation of a lighting fixture illustrating my new design.

I claim:

The ornamental design for a lighting fixture substantially as shown.

WILFRED B. GODDARD.
